UNITED STATES PATENT OFFICE.

MORRIS DENIS MONTECINO, OF SMOKE BEND, LOUISIANA.

AUTOMATIC-FIRE-ALARM ATTACHMENT.

1,277,633.

Specification of Letters Patent.

Patented Sept. 3, 1918.

Application filed July 29, 1916. Serial No. 112,077.

To all whom it may concern:

Be it known that I, MORRIS D. MONTECINO, a citizen of the United States, residing at Smoke Bend, in the parish of Ascension and State of Louisiana, have invented certain new and useful Improvements in Automatic - Fire - Alarm Attachments, of which the following is a specification, reference being had therein to the accompanying drawing.

This invention relates to an automatic electric fire alarm and has for its object the production of a simple and efficient means for closing an electric circuit after the temperature of the atmosphere surrounding the circuit closing device has reached a predetermined degree.

Another object of this invention is the production of a simple and efficient means whereby the circuit closing device may be adjusted to sound a signal at a predetermined temperature.

With these and other objects in view, this invention consists of certain novel constructions, combinations and arrangement of parts as will be hereinafter more fully described and claimed.

In the drawings:

Figure 1 is a front elevation of the indicator circuit closer.

Fig. 2 is a side elevation of the structure shown in Fig. 1.

Fig. 3 is a rear elevation of the structure shown in Fig. 1.

Fig. 4 is a section taken on line 4—4 of Fig. 1.

Fig. 5 is a section taken on line 5—5 of Fig. 4, looking in the direction of the arrow.

Fig. 6 is a section taken on line 5—5 of Fig. 4, looking in the opposite direction from the arrow.

Fig. 7 is a section taken on line 7—7 of Fig. 4.

Fig. 8 is an enlarged section taken on line 8—8 of Fig. 1.

Fig. 9 is a section taken on line 9—9 of Fig. 5.

Fig. 10 is a detail perspective of the contact block supported within the circuit closing casing.

Fig. 11 is a side elevation of the mechanism for closing the circuit for sounding a signal.

Fig. 12 is a detail perspective of the finger for closing the signal sounding circuit.

By referring to the drawings, it will be

seen that 1 designates the outer casing of the indicator which is provided with a front cover plate 2. This front cover plate 2 is provided with a glass face 3 and an indicating face 4 is placed in the rear of the glass face 3. An indicating hand 5 is carried by a shaft 6 which shaft 6 is supported within the casing upon the dial plate or indicating plate 4 as illustrated in Fig. 4 of the drawings and also passes through the supporting plate 7 of the bracket 8. The shaft 6 is provided with an enlarged portion 9 which enlarged portion 9 engages a thermostatic member 10, the thermostatic member 10 being in turn connected at its outer end to a binding block 11. This thermostatic member 10 is supported within the bracket 8 as clearly illustrated in Figs. 4 and 7 of the drawings.

A conducting arm 12 is connected to the shaft 6 so as to permit the shaft to readily rotate without swinging the arm 12, and this arm 12 is secured in an insulating bracket 13 as illustrated clearly in Fig. 4, the lower end of the arm being electrically connected to the conducting wire or other suitable cable 14 passing through the lower end of the casing 1. A contact arm or finger 15 is fixedly secured to the inner end of the shaft 6 and is adapted to rotate with the shaft 6 as the thermostatic member 10 expands under the increase of temperature. It should be understood that as the thermostatic member 10 is acted upon by the different degrees of temperature that this spring will cause the shaft 6 to rotate due to the lineal expansion and contraction of the spring.

An adjusting contact plate 16 is journaled in the rear plate 17 of the casing 1 and this plate fits snugly against the plate 17 as clearly illustrated in Figs. 4 and 5 of the drawings. A contact strip 18 is secured near the outer edge of this plate or disk 16 as is clearly illustrated by Fig. 5 and this strip 18 is adapted to be engaged by the contact arm 15 for closing the circuit therewith. The plate 18 is provided with a beveled forward end 19 and has a socket 20 formed therein to permit the contact arm 15 to fit within the socket and permit the circuit to be closed and also permitting the arm 15 to be held against movement except under extraordinary degrees of temperature wherein the arm 15 will move up the inclined faces 21 and come in contact with the stop knob or flange 22 formed in the opposite end of

the strip 18. An operating arm 23 is keyed to the sleeve 24 and may be swung so as to cause the disk 16 to be rotated to bring the contact strip 18, attached to disk 16 as aforesaid, in the desired position to sound a signal or alarm at a predetermined degree of temperature. A dial indicated by the numeral 24' is formed upon the rear face of the casing 1 so as to permit the operator 10 to readily set the indicator or contact device for the desired degree.

The casing 1 is provided with an eye 25 upon the top and bottom thereof, the top eye fitting over an arm 26 and the bottom eye fitting over an arm 27. The top arm 26 is provided with an upturned end 28 and a seal 29 is adapted to pass through the outer end of the arm 27 so as to hold the casing 1 against accidental or unauthorized 20 placement from the arms 26 and 27.

It, of course, should be understood that the circuit closing mechanism described and illustrated may be placed in any desired or convenient position and that any suitable 25 or convenient alarm or signal may be electrically connected thereto whereby this signal will be operated when the temperature surrounding the circuit closer reaches a predetermined degree.

30. For the purpose of convenience and illustration, a plurality of indicators above shown or illustrated may be employed, which indicators are adapted to be placed upon each dwelling or house in a certain 35 named locality for automatically electrically sounding an alarm in case of fire in any one of these dwellings.

An alarm box of any ordinary type is 40 adapted to coöperate with the electrical circuits above described, and a relay indicated by the numeral 39 (Fig. 11) is adapted to be placed within said alarm box; the wires 30 and 31 being connected to the binding 45 posts 40 formed upon the sounder for energizing the electro-magnets 41, whereby armature 42 will be actuated. The armature 42 carries a vertically-extending finger 43 (Fig. 11) which finger 43 carries, at its upper end, a contact fork 44 (see Fig. 12), 50 which contact fork 44 has a contact wire 45 stretching between the fork ends of the member 44. A vertically-extending standard 47 is mounted upon the base of the sounder-member and carries a contact finger 48, which is 55 electrically connected to wire 49, and wire

49, as well as wire 46 is adapted to be electrically connected to a general fire station or other general alarm.

What is claimed is:

1. An automatic alarm of the class described comprising a casing, a shaft supported within said casing, an indicating dial, a hand carried by said shaft and adapted to indicate the degree of temperature upon said dial, a thermostat carried by said shaft, a contact arm connected to said shaft, an electric circuit electrically connected to said contact arm, an adjustable electrical contact mounted within said thermostat, said adjustable electrical contact comprising a disk 60 journaled upon said casing, an arm for facilitating the rotation of said disk, a contact strip carried near the outer periphery of said disk and adapted to be engaged by said contact arm for closing a circuit there- 65 through.

2. An automatic alarm of the class described comprising a casing, a shaft supported within said casing, an indicating dial, a hand carried by said shaft and 70 adapted to indicate the degree of temperature upon said dial, a thermostat carried by said shaft, a contact arm connected to said shaft, an adjustable electrical contact 75 mounted within said thermostat, said adjustable electrical contact comprising a disk journaled upon said casing, an arm for 80 facilitating the rotation of said disk, a contact strip carried near the outer periphery of said disk and adapted to be engaged by 85 said contact arm for closing a circuit there- 90 through, said contact strip provided with a stop knob at one end thereof.

3. An automatic fire alarm of the class described comprising a casing, a contact arm, 95 means for controlling the rotation of said contact arm, a second contact means comprising a disk, a contact strip carried by said disk and adapted to be engaged by said contact arm, an indicator hand coöperating with 100 said contact arm, a dial for said indicating hand, a second dial upon the rear face of said casing, an arm connected to said contact disk and adapted to permit said contact strip to be set for contact with said contact 105 arm at a predetermined degree.

In testimony whereof I hereunto affix my signature.

MORRIS DENIS MONTECINO.
